UNITED STATES PATENT OFFICE.

GEO^RGE W. HUNTER, OF PHILADELPHIA, PENNSYLVANIA.

SEWING-MACHINE.

SPECIFICATION forming part of Letters Patent No. 232,971, dated October 5, 1880.

Application filed March 1, 1879.

To all whom it may concern:

Be it known that I, GEORGE W. HUNTER, of Philadelphia, county of Philadelphia, State of Pennsylvania, have invented Improvements 5 in Sewing-Machines, of which the following is the specification.

My invention relates to the details of construction of a reciprocating shuttle sewing-machine, the object being to reduce the complexity of the shuttle and feed moving apparatus and to reduce wear and friction.

In the drawings, forming a part of this specification, Figure 1 is an inverted plan of a sewing-machine with my improvements applied thereto. Fig. 2 is a cross-section on the line 1 2, Fig. 1; Fig. 3, a sectional elevation, showing the frame, except the part supporting and connected with the needle-operating mechanism; Fig. 4, a detached section; Fig. 5, a side view, and Fig. 6 a transverse section, showing a modification.

A is the base, B the overhanging arm, of a sewing-machine, the latter supporting a horizontal needle-driving shaft, C, upon which a cylindrical cam, D, is arranged diagonally, as shown. The cam is fitted to a socket in the head *a* of an oscillating lever or arm, E, which extends downward through a slot, *b*, in the bed-plate, and carries at the lower end a cross-bar, *c*, having spherical ends *e e*, Fig. 4, adapted to sockets in the ends of rods F and G. The rod F is connected to a pin, *f*, projecting from the shuttle-carrier H, which slides in a slot, *x*, in a vertical rib or flange, *d*, under the bed-plate, and is provided with fingers *i*, that hold the shuttle in contact with the face-plate *m*.

A stud, *n*, projecting from the side of the carrier opposite the pin *f*, extends into an inclined slot, *y*, in an arm, L, attached to or forming part of the bar G, which arm terminates in a finger, *p*, that extends across the reciprocating feed-plate I, a spring, *q*, riveted to which, tends to throw it downward and maintain the teeth below the work-plate.

There is a stud, *s*, on the feed-plate, and the side of the finger is inclined at *z*, so that as the rod moves forward the inclined face, striking the stud, will carry the plate in the direction of the arrow, Fig. 1, the extent of the feed being determined by the limit of the backward

movement of the plate I, regulated by moving forward and backward a slide, J, having a lug, *t*, bearing on the side of the spring *q*, which is pivoted on a pin, *q'*. The teeth of the feed-plate are thrown upward above the work-plate by the pressure of the finger *p* upon the under side of the plate I, or on the spring *q*, extending beneath the same, this resulting from the forward movement of the rod G, which causes 60 it to slide on the stud *n*, carrying its finger upward against the plate I.

It will be seen that the inclined cam D, for which an inclined crank might be substituted, not only imparts a longitudinal reciprocating movement to the end of the arm E, but it also turns or rocks the latter on its axis, so that the cross-bar *c* is turned successively to the positions shown in full and dotted lines, Fig. 1.

As the rod F is connected to the short arm 70 of the cross-bar *c*, the rocking of the latter varies but little the movement of said rod; but the opposite arm of the cross-bar attached to the rod G is of such a length that its oscillating motion, which takes place at the end of 75 each stroke, first thrusts the rod G forward, so as to bring its finger *h* in contact with the feed-lever, and then, after the forward movement of rods and shuttle, draws the rod G back prior to the return of the shuttle, so as 80 to depress the finger and carry it away from the plate I, which is therefore not operated on the return of the rod.

It will thus be seen that the lever or arm E imparts not only the reciprocating movement 85 to the shuttle, but carries the feed-operating rod G back and forth, and also, in connection with the spring, up and down, so that all the movements of the shuttle and feed are derived from the movements of the arm E and spring, 90 and that the peculiar operation of the arm E and cross-bar *c* results in imparting the movement to the feed at the time required—that is, while the needle is out of the cloth.

To compensate for wear the lever E and the 95 cross-bar *c* are divided transversely at *r*, as shown, and a set-screw, *u*, is arranged so that the divided portions may be spread apart on turning the same, to expand the spherical ends *e e* in their sockets.

To compensate for the wear of the bearing-faces of the cam D and head *a* the latter is

split longitudinally and provided with ears *v v*, through which extends a screw, *w*, by means of which the divided portions may be clamped closely to the cam, as the wear of the faces may 5 require.

To avoid the friction and nice fitting resulting from end bearings for the head *a*, I form an annular groove, *k*, in the cam *D*, and fit thereto a segment, *a'*, which is secured by a 10 screw, *b'*, to the head *a*, so as to be easily removed and replaced when worn.

It will be apparent that the rod *F* may be connected directly to the end of the lever *E*, the cross-bar *c* projecting only from one side.

15 I do not confine myself to the precise mode described of operating the feed-plate from the rod *G*, as other means may be used. For instance, I may pivot a segmental cam-arm, *L'*, to the stud *n*, Fig. 5, instead of using the sliding cam-arm described, connecting the rod *G* to the said segmental arm, so that the latter is turned up to come into contact with and lift the plate *I* on the forward movement, and tilted back out of the way prior to the backward 20 movement.

25 The side of the arm has a cam or beveled face, *6*, which, striking the lug *s* as the shuttle moves forward, carries forward the feed-plate.

I claim—

30 1. The combination of the feed-plate *I*, provided with a projecting stud upon its under side, a shuttle-carrier arranged to move transversely to such feed-plate, and mechanism for imparting to said shuttle-carrier a longitudinally-reciprocating motion, of a cam-arm car-

ried by the shuttle-carrier, and devices for elevating the said cam-arm to cause it to strike the feed-plate and stud when the shuttle-carrier is moving in one direction, and for depressing the same out of contact with the feed-plate 40 when moving in the opposite direction, substantially as described.

2. The combination, with the shuttle-carrier, feed-plate, shaft *C*, and inclined cam *D*, of the lever *E*, operated from the inclined cam, cross-bar *c*, rods *F* and *G*, and intermediate mechanism between said rods and the shuttle-carrier and feed-plate, substantially as described. 45

3. The combination, with a shuttle-carrier provided with a stud, *n*, and feed-plates *I*, having a stud, *s*, of rod *G*, provided with an arm, *L*, having an inclined slot, *y*, finger *p*, and beveled edge *z*, and mechanism for reciprocating the shuttle-carrier and operating the rod *G*, substantially as and for the purposes described. 50

4. The combination, with the shuttle and feed operating rods *F* and *G*, of the lever *E*, its cross-bar *c*, having spherical ends adapted to sockets in the said rods *F* and *G*, divided 55 at *r*, and provided with a set-screw, substantially as and for the purposes described.

In testimony whereof I have signed my name to this specification in the presence of two subscribing witnesses.

GEO. W. HUNTER.
